CLAIM

The ornamental design for a fluid control valve, as shown and described.

DESCRIPTION

FIG. 1 is a perspective view taken from the top, front and left side of a fluid control valve showing my new design;

FIG. 2 is a right side elevational view thereof, the left side being a mirror image of the right side shown;

FIG. 3 is a top view thereof;

FIG. 4 is a bottom view thereof;

FIG. 5 is a front view thereof; and

FIG. 6 is a rear view thereof.
